UNITED STATES PATENT OFFICE.

SOL. WILE AND HENRY LACASSE, OF ROCHESTER, NEW YORK, ASSIGNOR
TO THE BOTTLERS' SPECIALTY COMPANY, OF SAME PLACE.

FEED OR CARRIER MECHANISM.

SPECIFICATION forming part of Letters Patent No. 443,184, dated December 23, 1890.

Application filed July 27, 1889. Serial No. 318,932. (No model.)

To all whom it may concern:

Be it known that we, SOL. WILE and HENRY LACASSE, of Rochester, in the county of Monroe, in the State of New York, have invented 5 new and useful Improvements in Feeds or Carriers, of which the following, taken in connection with the accompanying drawings, is a full, clear, and exact description.

Our invention relates to an improved feed 10 or carrier, and has for its object the production of a simple and effective device which will readily feed the desired article to the required position; and to this end it consists, essentially, in impinging faces for engaging 15 the article to be fed, a gage for causing the fed article to assume the desired position or plane in relation to the impinging faces, a lock for retaining said arms in their engaging position, and a discharge for discharging 20 the fed article.

It furthermore consists in the detail construction and arrangement of the parts, all as hereinafter more particularly described, and pointed out in the claims.

25 In describing our invention reference is had to the accompanying drawings, forming a part of this specification, in which like letters and figures indicate corresponding parts in all the views.

30 Figure 1 is a plan view of our improved carrier and its actuating mechanism. Fig. 2 is an enlarged plan view of the actuating mechanism of the carrier, illustrating the detail construction and arrangement thereof.

35 Fig. 3 is an elevation of the parts shown in Fig. 2. Fig. 4 is an elevation further illustrating the operating mechanism of the feed or carrier. Fig. 5 is a plan view of a portion of the mechanism illustrated in Fig. 4. Fig.

40 6 is a longitudinal vertical section taken on line $x-x$, Fig. 1. Fig. 7 is a horizontal section taken on line $y-y$, Fig. 6. Fig. 8 is a plan view of Fig. 6, and Figs. 9 and 10 are respectively plan and elevation of the gage and dis- 45 charge for our improved carrier.

The frame A, to which the carrier is attached, may be of any desirable form and construction, but is here represented as the frame of our improved machine for corking 50 bottles and wiring the corks thereto, de-

scribed and claimed in our application of even date herewith. Supported in the bracket A', formed or provided upon the frame, is the supporting-rod B, preferably of cylindrical shape, and prevented from turning in the bracket A' by a set-screw b. Mounted upon this rod B are disks C, between which are pivoted at d the oscillating arms D, arranged in pairs upon said disks. Pivoted at e to the outward free extremities of said arms 6c are the impinging faces E, preferably provided on their adjacent bearing-surfaces with yielding plates E', formed of rubber or other suitable material. At the opposite extremities of said arms D, and pivoted thereto at 65 f, are the toggle-levers F, pivoted to each other at f'. A cam G contacts with these toggle-levers and preferably with a roller f'', provided at the pivotal point thereof. The pivotal pin f' of the toggle-levers extends 70 upwardly beyond the upper disk C into a camway H' of the cam H. The operating-surfaces of the cams H and G are of the same contour, the cam G serving to straighten the toggle-levers F and lock the impinging faces 75 E against the fed article, and the cam H serving to separate the impinging faces E by forcing the rollers f'' into a cut-out G' of the cam G. In order to guide the toggle-levers in said operation, we extend the common pivotal pin 80 f' thereof into a groove C' in the lower disk C. This pin is preferably provided with a roller f'', guided in the slot or recess C'.

The pivotal pins d of the arms D are preferably adjustable toward each other to adapt 85 the said arms for various sizes of articles to be fed. This adjustment is preferably secured by providing a concentric slot d' in the disks C, in which said pins are supported. The pins are retained in the desired adjustment by means of a nut or other clamping device d'', secured at the upper extremity of the pivotal pin, which draws the parts together and retains them by friction. 90

In order to adapt the bearing-faces to the 95 various contour of the articles to be fed, it will be noticed that they are pivoted to the arms D, which allow them to readily adjust themselves, as desired.

By reference to Fig. 6 it will be seen that 100

the cams G and H are rigidly secured to the supporting-rod B, and that the feeding-arms rotate around said bar. Rigidly secured by a set-screw *i* to the rod B is the bracket I, in the free extremity I' of which is guided a rod I², having an enlarged extremity I³, between which and the extremity I' of the bracket I we interpose a spring I⁴. At a desirable distance above said enlarged or supporting extremity I³ are the levers U, which will be presently described. These levers are a desired distance above the plane of the bearing-faces E, and when the article to be fed is placed upon the yielding support I³ the same is pressed until the top or other portion of said article contacts with said levers, which thus form a gage and adjust the article to its desired position.

It will be understood, as illustrated in the drawings, that when the article to be fed is placed upon the support I³ the arms D are at their open adjustment, and the said article is readily forced between the open bearing-faces E. Immediately after the placing of said article the peculiar shape of the cam G forces said bearing-faces tightly against the article to be fed, and it is thus secured in the desired plane in relation to the carrier-arms. This is a feature of great advantage and allows any desirable operation to be readily and quickly performed upon said article by any particular construction of machine or device to which said article is fed or carried.

Depending from the lower plate C is the hub C³, which is supported in a hollow hub J by a set-screw *j*. This hub J projects upwardly from a plate J', provided with notches *j'*. Mounted above the plate, and preferably pivoted to the hub J, is the lever K, having a dog *k* pivoted thereto at *k'*, with its free end adapted to engage the notch *j'* of the plate J'. The lever K is pivoted at *k'* to the bar L, jointed at *l* to a bar L', supported in a bracket L², secured to the table A. At the free extremity of the bar L' is a lug L³, between which and the bracket L² we interpose the spring L⁴, which constantly forces said cam away from said bracket.

Mounted upon a shaft M, secured by brackets (not illustrated) to the frame A, is an operating-gear M', having a cam-tooth *m* which contacts with the lug L³, compresses the spring L⁴, and rotates the disk or plate J' a desired distance around its supporting-rod B. It will thus be seen that the carrier-arms are rotated around the bar B, and are operated to feed the desired article from the support I³ a desired distance around said bar B. The disk J' is locked in the desired position by means of a sliding lock N engaging notches *j'* in the peripheral edge of the said disk or plate. This sliding bar N is guided at one extremity in a bracket N' and at the other by the bracket L². Formed upon said rod is a shoulder or washer N², between which and the bracket L² is interposed a spring N³, constantly forcing said lock into the notch *j'*. The free extremity of the

bar N is hinged at N⁴ to a lever N⁵, pivoted at *n* to a bracket *n'*, mounted upon the main frame. The upper extremity N⁶ of said lever is bent forward toward a suitable cam O, provided with a projecting tooth *o*, which rocks said extremity backward, and thus draws the sliding rod N backward against the action of the spring N³ and withdraws the locking extremity thereof from the notch *j'*. This cam-tooth *o* is so timed in relation to the cam-tooth *m* that the lock is withdrawn just before the operation of the actuating-rod L. The cam-tooth *o* is of short operation, and immediately after the commencement of the rotation of the plate J' the spring N³ forces the extremity of the lock against the periphery of said plate, and when the succeeding notch *j'* is registered therewith the plate is automatically locked in its adjusted position. It will thus be seen that an intermittent movement is given to the carrier, but it will be understood that, if desired, the same might move continuously.

By reference to Fig. 6 it will be observed that the frame supporting the carrier-arms is adjustable in relation to the hub J. This allows the carrier-arms to be moved toward the support I³, and adjust the device to various sizes or heights of articles to be fed or carried. Suitably arranged in relation to the rod B is a support P for the fed article, which is placed thereabove when the arms D are registered therewith. As previously described, the top or other portion at the upper extremity of the fed article is brought to the desired plane, and it frequently happens that the bottoms of said articles are not in the same plane.

In order to provide for the varying planes of the different fed articles, we prefer to make the support P movable up and down and preferably adjustable to the desired height. This movement is preferably produced by mounting said support upon a screw-shank P', guided in an opening A² of the bracket A'. Bearing upon the top of said bracket A' is a gear P², provided with a central opening *p*, having screw-threads engaged with the threads of the screw-shank P'. Meshing with this gear P² is the segment Q, which is operated to rock said gear first in one direction and then in the opposite. This segment Q, as best shown in Fig. 5, is pivoted around the depending hub J⁴ of the plate or disk J'. Provided upon the hub Q' of the segment Q is an arm Q², pivoted to which at *r* is the bar R, hinged at *t* to a sliding bar T. Secured at the outward extremity of this bar T is the lug T', against which bears a cam-tooth *m'*, provided upon the gear M'; previously described. This cam-tooth *m'* forces forward the lug T' against the action of a spring T², interposed between said lug and the supporting-bracket L². Upon the forward movement of the rod R the segment is forced in the direction indicated by the arrow and the gear lowers the support P by

means of the shank P' . Immediately after the disengagement of the cam-tooth m' and the lug T' the spring T^2 retracts said segment, and thus forces upward the support P against 5 the bottom of the fed article. As the motor force of this movement is a spring, it will be understood that should the lower extremity of the fed article extend farther than usual the support would then be stopped as soon as 10 contacted, and as the screw-shank is engaged with the gear P^2 the support cannot be forced downward unless it is rotated, thus allowing any operation to be performed upon the said article. The support P is preferably loose 15 upon its shank P' , and is formed with a guideway or groove p' , registering with a guide or rib p^2 , secured to the frame A , thus causing said support to move up and down without rotating.

20 The levers U , which, as previously described, form a gage for the fed article when being fed upon the yielding support I^2 , are preferably mounted in a guideway 1 of the disk 2 , loosely mounted on the rod B . These levers U are 25 pivoted at u to a supporting rod or pin U' , preferably depending below said levers. As shown in Fig. 7, these depending bars U' extend through the upper plate C , and are thus rotated around the bar B by the movement of 30 said plate. Mounted above the cam H and rigidly secured to the rod B is a cam V , having a camway V' arranged in the periphery thereof. Provided upon the downwardly-projecting rod U' is a stud or roller U^2 , which 35 rides in said camway V' . As the disks C rotate the levers U around the rod R , the levers U are forced upward or downward, according to the form of the camway V' in the cam V . This camway is of suitable form to cause 40 the said levers U to stand at the desired plane above the fed article upon engagement of the same with the feeding-arms D , as previously described. It is also preferably of such a construction as to cause said arms to descend below the top plane of the fed article and support the upper extremity thereof during any 45 operation performed thereupon. This downward movement may occur at any desired place, but preferably occurs just before the 50 registration of the fed article with the support.

Upon reference to the section-line on which Fig. 6 is taken it will be understood that the support shown in said figure is in a plane back of the plane of the fed article, which article 55 is illustrated as moved forward from above the support. During this movement of the bottle the levers which embraced the top of the bottle when the same was over said support have by the camway V' been moved upward from around said bottle, and after the levers U are sufficiently removed above the fed article the camway V' then forces said levers U downward and contacts them with the top of the bottle. Before this last operation 60 of the levers U the cut-out G' of the cam G is registered with the rollers f^2 of the toggle-levers F and the impinging faces E are loos-

ened from engagement with the fed article. It will then be readily understood that when 70 said levers U are brought down upon the top of the fed article the same is readily forced or discharged from the arms D . When acting as a gage, the levers U are brought closely together, and when acting as a support for the top of the fed article said levers are forced 75 apart in order to allow them to encircle the bottle. These operations of the levers U are brought about by a cam W , rigidly secured to the rod B and of suitable contour to close or approximate the levers toward and away 80 from each other at the desired points. These levers U , as shown in Figs. 8 and 9, are formed with rearwardly-projecting extremities U^8 , pivoted to which at w are the toggle-levers W^2 , pivoted to each other at W' . Projecting 85 upwardly from the pivotal point of the toggle-levers W^2 is the pin Y , guided in a guide or slot y' of a disk y , secured above the cam W . As previously described, the cam W closes or approximates the levers U and 90 brings about this movement by straightening the toggle-levers W^2 . Said levers are separated by means of a lever X , pivoted at x to the underneath side of the plate y . This lever is formed with one arm x' bearing against 95 the outward face of the upwardly-projecting pin Y . The opposite extremity of said lever contacts with a pin Z , secured upon the cam W . This cam W is stationary, and as the 100 said arm of the lever X is contacted with the pin Z it is rocked outward and the opposite extremity is rocked inward, forcing inward the projection Y and opening the levers U . This pin is placed upon said cam at the 105 desired point to bring about this movement of the levers U , in order that they may encircle the fed article.

The operation of our invention will be readily perceived from the foregoing, and it will be understood that the fed articles are placed 110 with their tops in the desired plane in relation to the feeding-arms and that they are then fed to mechanism, which operates upon them as desired, and they are then finally discharged from the carrier. This carrier or feed is especially applicable, as stated, for our improved 115 machine for corking bottles and wiring the corks thereto. In this machine it is necessary that the tops of the bottles shall be brought to the desired plane in relation to the corking and wiring mechanisms of the said machine. It will be seen that at Fig. 1 we have illustrated in plan this twisting mechanism S of 120 our machine for corking bottles and wiring the corks thereto; but it is not thought necessary to describe said mechanism in our present invention. It will be understood, however, that we do not limit our invention to its use upon any particular form of machine; neither do we limit the carrier or feed to the 125 relative arrangement and construction of its parts, since it will be understood that the relative arrangement of the feeding-arms and the gage and discharge for the fed article 130

might be varied from that described, according to the requirements of the machine of which said carrier forms a part. It will also be understood that considerable change may 5 be made in the detail construction and arrangement of the parts without departing from the spirit of our invention.

Having thus fully described our invention, what we claim as new, and desire to secure by 10 Letters Patent, is—

1. In a feed or carrier, the combination of a support or plate, oscillating arms pivoted to said plate and provided at one extremity with bearing faces or jaws for impinging the 15 article to be fed, toggle-levers connected to the opposite extremities of said arms, and mechanism for straightening the toggle-levers and locking said faces against said article, substantially as set forth.
2. In a feed or carrier, the combination of a support or plate, oscillating arms pivoted to said plate and provided at one extremity with bearing faces or jaws for impinging the article to be fed, toggle-levers connected to the 25 opposite extremities of said arms, mechanism for straightening said toggle-levers for locking said faces against the said article, and mechanism for unlocking the toggle-levers and causing the said article to be released by 30 said bearing-faces, substantially as described.
3. In a feed or carrier, the combination of a support or plate, oscillating supports or levers pivoted to said plate and movable toward and away from the article to be fed, mechanism 35 for operating said levers, and bearing faces or jaws hinged to said levers for grasping the said article and adjusting themselves thereto, substantially as specified.
4. In a feed or carrier, the combination of a 40 support or plate, oscillating levers pivoted to said plate, bearing-faces pivoted to said oscillating levers for grasping the article to be fed and adjusting themselves thereto, a toggle connecting the opposite extremities of 45 said levers, mechanism for straightening said toggle, and mechanism for unlocking the toggle and separating the said faces from the said article, substantially as and for the purpose described.
5. In a feed or carrier, the combination of a 50 support or plate, bearing faces or jaws pivoted to said plate for impinging the article to be fed, a toggle connected to said faces, mechanism for straightening said toggle and locking 55 said faces or jaws against the said article, and a discharge for discharging said article from said faces, substantially as and for the purpose specified.
6. In a feed or carrier, the combination of a 60 support or plate, bearing faces or jaws pivoted to said plate for impinging the article to be fed, a toggle connected to said bearing-faces, mechanism for straightening said toggle and locking said faces or jaws against the 65 said article, mechanism for unlocking the toggle and operating the said faces to release the impinged article, and a discharge timed

with said mechanism for unlocking the toggle, substantially as and for the purpose described.

7. In a feed or carrier, the combination of a support or plate, oscillating levers movable toward each other, impinging faces or jaws mounted upon said levers at one extremity thereof, a toggle between the opposite extremities of said levers, mechanism for straightening said toggle and locking said bearing faces or jaws against the article to be fed, mechanism for unlocking said toggle and releasing the said article from impingement, and a discharge movable toward said jaws or faces for discharging the said article, substantially as described.

8. In a feed or carrier, the combination of bearing faces or jaws for impinging the article to be fed, a toggle connected to said bearing-faces, a gage for bringing the article to be fed to the desired plane in relation to said bearing-faces, and mechanism for straightening said toggle and locking said faces against 90 said article after the adjustment thereof, substantially as specified.

9. In a feed or carrier, the combination of oscillating levers, bearing faces or jaws mounted upon one extremity of said levers, 95 toggle-levers connecting the opposite extremities of said levers, a gage for bringing the article to be fed to the desired plane in relation to said bearing faces or jaws, and mechanism for straightening the toggle after the 100 adjustment of said article, substantially as described.

10. In a feed or carrier, the combination of a gage for bringing to the desired plane the article to be fed, carrier-arms for grasping 105 said article, toggle-levers for locking the arms in said position, and mechanism for actuating the carrier-arms to feed said article, substantially as and for the purpose specified.

11. In a feed or carrier, the combination 110 of a series of gages arranged at intervals upon a support, carrier-arms movable toward each other and arranged beneath said gages, and mechanism for approximating the operating extremities of said carrier-arms when 115 the article to be fed is engaged with said gages, substantially as specified.

12. In a feed or carrier, the combination of a series of gages, arranged in a circle at intervals, impinging faces or jaws arranged 120 beneath said gages, mechanism for revolving said gages and impinging faces, a fixed cam for approximating together said impinging faces to hold the article to be fed, and a cut-out in said cam for separating said faces 125 when the said article is engaged with the gage in order to allow of the ready entrance of said article between said impinging faces, substantially as set forth.

13. In a feed or carrier, the combination of 130 bearing faces or jaws for impinging the article to be fed, a toggle connected to said bearing-faces, a gage for bringing the article to be fed into the desired plane in relation to

said faces, mechanism for straightening said toggle and locking said faces upon the adjusted article, and a discharge for discharging said fed article, substantially as specified.

5 14. In a feed or carrier, the combination of carrier-arms, a cam for operating said arms, connections, substantially as described, between said arms, an operating-cam, a cut-out in said cam for registering with said connections and opening the carrier-arms, a gage engaged with the article to be fed when said connections to the carrier-arms are at one extremity of said cut-out, and a discharge movable toward and away from the bottle, and 15 connections between said cam and discharge, whereby the discharge is timed with the carrier-arms, substantially as specified.

15 15. In a feed or carrier, the combination of a gage for bringing to the desired plane 20 the article to be fed, carrier arms or jaws for grasping said adjusted article, a toggle for locking said arms in said position, mechanism for unlocking said arms, and a discharge for discharging said article, substantially as set 25 forth.

16 16. In a feed or carrier, the combination of impinging faces or jaws movable toward and away from each other for grasping and releasing the article to be fed, a gage supported in a different plane from said arms, mechanism for holding said gage fixed when said article is registered with the carrier-arms, and mechanism for moving said gage toward the carrier-arms and contacting said 35 gage with said article when the same has been fed to the desired position, substantially as set forth.

17 17. A carrier or feed having a gage for forcing to the desired plane the article to be fed, and 40 arms or jaws for impinging said article when forced to the desired plane, said arms or jaws being movable toward or away from the gage for adapting the same to different-sized articles, substantially as and for the purpose described.

45 18. In a feed or carrier, the combination of a stationary yielding support, a revoluble support, carrier-arms mounted on said latter support and arranged at intervals thereon, gages 50 also mounted on said latter support and adapted to register with said yielding support, and mechanism for impinging the carrier-arms against said article when brought to the desired plane by said gages, substantially as 55 specified.

19 19. In a feed or carrier, the combination of a movable frame, carrier-arms mounted upon said frame, a toggle for locking said carrier-arms against the article to be fed, and a support 60 beneath said articles in the path of the carrier for preventing their discharge from the toggle-locked levers, substantially as and for the purpose set forth.

20 20. In a feed or carrier, the combination of 65 arms or jaws for impinging the article to be fed, a gage for forcing said article to the desired plane, a toggle for locking said jaws

against the said article, and a support beneath said jaws for preventing the discharge of said article, substantially as and for the purpose specified.

21. The combination, with a carrier or feed having movable arms or jaws for impinging the article to be fed, of a support adjustable toward the said carrier or feed, and connected mechanism for automatically adjusting said support to the fed article, substantially as specified.

22. In a feed or carrier, the combination of a movable frame, arms or jaws mounted upon said frame for impinging the article to be fed, a support adjustable toward the said carrier or feed, connected mechanism for automatically adjusting said support to the fed article, and a discharge for discharging said article from the carrier-arms, substantially as specified.

23. In a feed or carrier, the combination of a movable frame, carrier arms or jaws mounted upon said frame for impinging the article to be fed, a support adjustable toward said carrier or feed, connected mechanism between the carrier and said support for withdrawing the support from the carrier before the movable arms or jaws are aligned therewith, and for approximating said support to the carrier after the alignment of the carrier arms or jaws with the said support, and a discharge for forcing said article from the carrier-jaws, substantially as described.

24. The combination of an intermittently-revolving disk or plate, mechanism for revolving said disk, a frame adjustable toward and away from said disk and revolved thereby, carrier arms or jaws supported by said frame, and toggle-levers connecting said arms for moving them toward and away from each other for grasping and releasing the article to be fed, substantially as described.

25. The combination of a carrier or feed, a gage for forcing to the desired plane the article to be fed, and a support to which the articles are fed, said carrier and gage being adjustable toward and away from the support, substantially as and for the purpose described.

26. A feed or carrier having pivoted arms for impinging the article to be fed, the pivot-points of said arms being adjustable toward each other to adjust the arms, substantially as and for the purpose specified.

27. In a feed or carrier, the combination of pivoted impinging-arms having their pivot-points adjustable toward each other, and connected mechanism for actuating said arms to grasp and release the article to be fed, substantially as and for the purpose described.

28. In a feed or carrier, the combination of a revoluble supporting plate or disk, carrier-arms pivoted upon said plate, a slot in said plate for the pivot-point of the said carrier-arms, a clamp for retaining the said pivot-point in its adjusted position, and mechanism for operating said carrier arms or jaws, substantially as and for the purpose specified.

29. In a feed or carrier, the combination of

impinging arms or jaws having their pivot-points adjustable toward each other, a toggle connecting said arms, and a cam for straightening said toggle and locking the said arms 5 upon the article to be fed, substantially as and for the purpose specified.

30. In a feed or carrier, the combination of bearing faces or jaws for impinging the article to be fed with a portion thereof projecting beyond said faces, a toggle connected to said faces, and mechanism for straightening said toggle and locking said faces upon the said article with a support for engaging the projecting portion of said fed article, substantially as specified.

31. In a feed or carrier, the combination of oscillating levers, bearing faces or jaws provided upon said levers for engaging the article to be fed and allowing a portion thereof 20 to project, levers for engaging said projecting portion of the fed article, a toggle connected to said latter levers, and connected mechanism for operating said parts in due order, substantially as specified.

32. In a feed or carrier, the combination of oscillating arms or jaws for impinging a portion of the article to be fed, the remaining portion of said article projecting beyond said arms or jaws, a support in a different plane 30 to that of the impinging arms or jaws, and mechanism for approximating said support to the plane of said arms or jaws, substantially as and for the purpose specified.

33. In a feed or carrier, the combination of 35 an intermittently-revolving frame or support,

carrier arms or jaws mounted upon said support for grasping the article to be fed, a toggle connected to said arms or jaws at one extremity, and a stationary cam for operating the foregoing parts in due order, substantially 40 as and for the purpose set forth.

34. In a feed or carrier, the combination of a support, mechanism for intermittently operating said support, a lock for retaining said support in its adjusted position, arms or jaws 45 pivoted to said frame for grasping the article to be fed, a toggle connected to said arms at one extremity, and mechanism for operating said toggle, substantially as specified.

35. In a feed or carrier, the combination of 50 a frame or support, a lock for locking said frame or support, mechanism for operating the carrier, mechanism for withdrawing the lock before the operation of said actuating mechanism, arms or jaws pivoted to said 55 frame or support for grasping the article to be fed, a toggle connected to said arms or jaws at one extremity, and mechanism for operating said toggle, substantially as and for the purpose specified.

In testimony whereof we have hereunto signed our names, in the presence of two attesting witnesses, at Rochester, in the county of Monroe, in the State of New York, this 23d day of May, 1889.

SOL. WILE.
HENRY LACASSE.
